UNITED STATES PATENT OFFICE.

J. P. A. HAVARD AND J. B. BOURGOISE, OF PARIS, FRANCE.

IMPROVEMENT IN PORTABLE FILTERS.

Specification forming part of Letters Patent No. 34,492, dated February 25, 1862.

To all whom it may concern:

Be it known that we, JULES PANCOME ALFRED HAVARD and JEAN BAPTISTE BOURGOISE, both of Paris, in the Empire of France, have invented a new and Improved Filtering Apparatus; and we do hereby declare that the following is a full, clear, and exact description of the same, reference being had to the accompanying drawings, making a part of this specification, in which—

Figure 1 is a side elevation of our improved filtering apparatus in condition for use. Fig. 2 is a central vertical section of the same. Fig. 3 is an elevation of the apparatus taken out of its case. Fig. 4 is an elevation of the case, and Fig. 5 is a plan of the same. Fig. 6 is an elevation of the packing case or bucket. Fig. 7 is a central vertical section of the apparatus folded or contracted and cased for transportation.

Similar letters of reference indicate corresponding parts in the several figures.

The object of this invention is to obtain a filtering apparatus of such form and made of such material as to be capable of being readily folded or contracted into a small compass, whereby it may be put into a bucket or case of one-half of its liquid-containing capacity and thereby made easily transportable, the apparatus being especially designed for domestic and army purposes.

The invention consists of two receptacles formed of any suitable water-proof fabric and separated from each other by a suitable filtering medium, which is confined between two wire-gauze or perforated metallic disks; also, in the manner of supporting the upper receptacle, and also in the manner of packing the apparatus for transportation.

To enable others skilled in the art to fully understand and construct our invention, we will proceed to describe it.

A represents a sack, which is made of hemp cloth coated on the inside with caoutchouc to render it water-proof. Said sack may be made of any suitable water-proof fabric. The upper and lower edges of the sack are clamped between two annular metallic rings *a a' b b'*, and thereby securely fastened. The said rings when the sack is distended cause it to assume a cylindrical form. On the inside and about one-third the length of the sack

from the bottom upward it is divided by a suitable filtering medium into two compartments, forming receptacles B C, the former being above the filtering medium for the reception of the water to be filtered, and the latter below for the reception of the filtrate. The filtering medium D consists of layers of wool, or it may be of any other suitable material or substance, interposed between two wire-gauze or perforated metallic disks *c d*, said disks being soldered or otherwise attached on opposite sides of an annular ring *e*, forming a case for the filtering medium, which case is fastened in position in the sack by a band or ring *f*, which encompasses the sack opposite the case of the filtering medium and clamps it between the outside of the inner ring *e* and inside of the outer ring *f*. The receptacle C is closed at its lower end by a metallic bottom *g*, which is fastened by solder or otherwise to the top of the inner bottom ring *b*.

E is a faucet, which is secured by a screw-thread, or it may be in any other suitable manner, to the bottom of the receptacle C, and is for the purpose of drawing the filtrate therefrom.

A flexible tube *h*, open at both ends, is attached at its upper end to the ring *a*, and at its lower end to a metallic tube *i*, which passes through the filtering medium near its outer edge, forming a communication between the receptacle C and external air, and thereby affording means for a proper ventilation of the receptacle. The inner ring *a* at the upper end of the sack is provided with two ears *j k*, placed opposite each other, and to which an ordinary bucket-bail *m* is fastened, whereby the upper part of the sack forming the receptacle B is suspended from an arm, as will be hereinafter fully described. Said bail also enables the apparatus to be carried about in the hand and to be used like a common bucket for carrying water.

H represents a cylindrical metallic case, which is for the purpose of supporting the apparatus when it is desired for ordinary use in the house or camp, and in which it is folded when it is to be packed for transportation. The receptacle C may be supported by the bottom edge of the ring *f*, resting on lugs or brackets projecting inwardly from the upper

edge of the case, or it may be supported merely by friction, as shown in the accompanying illustration.

The flexible sides of the receptacle B are retained in a distended or stretched form when the apparatus is desired for use by the telescopic sliding tubes n o p q, the lower section q of which is attached to one side of the case, or it may be attached to the ring. The upper section n is provided with a horizontal arm n', which extends over the center of the receptacle and terminates in a hook on which the bail of the apparatus is caught, and the flexible sides of the receptacle B thereby supported in a distended form.

I is a common pail or bucket, in which the apparatus is packed when it is desired to transport it.

The water to be filtered is placed in the receptacle B, when it percolates through the interstices of the filtering medium into the receptacle C, from which it is drawn off, as it is desired for use, through a faucet hereinbefore described.

When the pores or interstices of the filtering medium become clogged with sediment, it is necessary to have the material cleansed. This is effected, after removing the faucet and

stopping up the opening in the bottom of the receptacle by a plug or other suitable device, by pressing on the bottom of the receptacle, causing the filtrate to pass forcibly through the interstices of the filtering material, thereby washing and cleansing the same in the most thorough manner.

Having thus described our invention, what we claim as new, and desire to secure by Letters Patent, is—

1. A filtering apparatus consisting of two receptacles B C, formed of flexible waterproof fabric, filtering medium D, and wire-gauze or perforated metallic disks e d, when combined and arranged in the manner substantially as described.

2. The sliding tubes n o p q, arm n', and bail m, arranged, in combination with receptacle B, to operate substantially as described.

3. The flexible sides of the receptacles B C, sliding tubes n o p q, case H, and packing case or bucket I, combined and arranged in the manner and for the purpose set forth.
